(57) **CLAIM**

The ornamental design for a undercabinet plug-in mount, substantially as shown and described.

DESCRIPTION

FIG. 1 is a front, top, left-hand side perspective view of an undercabinet plug-in mount comprising a new, original and ornamental design;

FIG. 2 is a front view of an undercabinet plug-in mount comprising the new, original and ornamental design;

FIG. 3 is a left-hand side view of an undercabinet plug-in mount comprising the new, original and ornamental design;

FIG. 4 is a right-hand side view of an undercabinet plug-in mount comprising the new, original and ornamental design;

FIG. 5 is a top view of an undercabinet plug-in mount comprising the new, original and ornamental design;

FIG. 6 is a bottom view of an undercabinet plug-in mount comprising the new, original and ornamental design; and,

FIG. 7 is a rear view of an undercabinet plug-in mount comprising the new, original and ornamental design.

The broken lines shown in the drawings illustrate unclaimed portions of the article and form no part of the claimed design.
